[57] CLAIM

The ornamental design for a base cup for a plastic container, as shown and described.

DESCRIPTION

FIG. 1 is a side elevational view of a base cup for a plastic container showing my new design, the bottle represented by broken lines being for illustrative purposes;

FIG. 2 is a top plan view thereof; and

FIG. 3 is a bottom plan view thereof.

—FIG. 1

—FIG. 2

—FIG. 3
